UNITED STATES PATENT OFFICE

170,668

HOLDER FOR SEWING ACCESSORIES

Thomas V. Tierney, Belleville, and Samuel Gaccione, Nutley, N. J.

Application April 20, 1953, Serial No. 24,569

Term of patent 14 years

(Cl. D3—19)

To all whom it may concern:

Be it known that we, Thomas V. Tierney and Samuel Gaccione, citizens of the United States, residing at Belleville and Nutley, respectively, in the county of Essex and State of New Jersey, have invented a new, original, and ornamental Design for a Holder for Sewing Accessories, of which the following is a specification, reference being had to the accompanying drawing, forming part thereof.

We claim:

The ornamental design for a holder for sewing accessories, as shown.

THOMAS V. TIERNEY.
SAMUEL GACCIONE.
